(57) CLAIM

We claim the ornamental design for a sport mini mister fan, as shown and described.

DESCRIPTION

FIG. 1 is a perspective view of the mini mister fan according to the present design;

FIG. 2 is a front view of the present design;

FIG. 3 is a top view of the present design; and

FIG. 4 is a bottom view of the present design; and,

FIG. 5 is a right side view of the present design, a corre-
thereof.
